(57) **CLAIM**

We claim the ornamental design for a wireless charger, as shown and described.

DESCRIPTION

FIG. 1 is a front perspective view of a wireless charger showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a bottom perspective view thereof;

FIG. 9 is an enlarged view of the encircled portion 9 of FIG. 2;

FIG. 10 is an enlarged view of the encircled portion 10 in FIG. 2;

FIG. 11 is an enlarged view of the encircled portion 11 in FIG. 8;

FIG. 12 is an enlarged view of the encircled portion 12 in FIG. 8; and,

FIG. 13 is a bottom perspective view of the wireless charger shown in a state of use.

The equal-length broken lines on the wireless charger depict portions of the wireless charger that form no part of the claimed design.

In FIG. 13, the equal-length broken lines showing a cord and connector depict environmental subject matter only, and form no part of the claimed design.

1 Claim, 13 Drawing Sheets
